UNITED STATES PATENT OFFICE.

JOHN R. KLIN, OF DAYTON, OHIO, ASSIGNOR TO THE BIKE FOLDING BOX COMPANY, OF DAYTON, OHIO, A CORPORATION OF OHIO.

GARMENT BAG.

Application filed July 26, 1926. Serial No. 124,929.

My invention relates to garment bags and in particular to a self-opening garment bag.

It is the object of my invention to provide a self-opening garment bag which will stay in open condition for the insertion of the garments.

It is a further object of my invention to provide such self-opening mechanism which will also serve as a support for the garment 10 hangers and will enable a plurality of such hangers and garments thereon to be placed in the bag, thus increasing the capacity of the bag.

It is a further object of my invention to 15 provide a novel form of clamp for clamping the open sides of the bag to form a tight enclosure.

Referring to the drawings:

Figure 1 is an end elevation of the bag 20 blank;

Figure 2 is a plan view of the blank;

Figure 3 is a side elevation of the bag in open spread condition;

Figure 4 is a rear elevation of the bag 25 in open condition;

Figure 5 is an end elevation of the bag in closed condition;

Figure 6 is a section on the line 6—6 of Figure 4;

Figure 7 is a section on the line 7—7 of Figure 5;

Figure 8 is a plan view of the new form of clamp of my invention;

Figure 9 is a side elevation thereof;

Figure 10 is a perspective of the bag when 35 in folded condition for shipping;

Figure 11 is a section on the line 11—11 of Figure 4;

Figure 12 is a rear elevation in detail partially broken away of the combined bag 40 support and spreading mechanism;

Figure 13 is a section on the line 13—13 of Figure 11;

Figure 14 is a section on the line 14—14 45 of Figure 11;

Figure 15 is a perspective of the clip with the tape being removed.

Referring to the drawings in detail, the blank is composed of a series of rectangular 50 sections for the front panel, designated 1, 2, 3 and 4. An upper overlapping flap 5 is provided and a lower flap 6. A double folding flap consisting of sections 7 and 8 is provided on the free edge which is adjacent the mouth of the bag. The rear wall

of the bag is formed into a series of rectangular sections 9, 10, 11 and 12 corresponding to the sections 1, 2, 3 and 4. On one of these rear sections is mounted a plate of paper 13 which is saturated with a compound to prevent moths and other insects from disturbing the clothing in the bag. 60 The free edge which is adjacent the side mouth of the bag is provided with a folding flap consisting of the sections 14 and 15 which cooperate with the sections 7 and 8 for closing the mouth of the bag.

On this flap there are located by tapes 16 the clamps 17 which clamp the folds along the mouth of the bag to seal the bag. 70 It is generally preferable to have one of these clamps to each one of the panels as the bag folds along the lines 18 which separate the respective panels.

The reason for the folding of the bag in 75 this particular fashion will be hereinafter explained.

For purposes of general reference to the bag as a whole, the rear of the bag will be designated 19 and the front of the bag 20. 80

When the bag is folded, it will be observed that the flaps are folded one over the other to form a compact structure, better illustrated in Figure 7, over which the clamp is slipped. This clamp consists of a U-shaped member having the legs 21 and 22. 85 It is made of spring steel. The leg 22 is longer than the leg 21 and is upturned at its end, as at 23, so that that end will overlap the folded end 24 of the folded edges of the bag.

This extreme end is also provided with a wedge-shaped slot 25 terminating in an eye 26 in which is located the supporting tape 16. This particular form of eye is such that 90 the relatively broad tape cannot pass out through the narrow exit opening from the eye 26 to the wedge-shaped slot 25 unless the tape has been especially manipulated so that there is no possibility of the clips falling off 100 of the bag when once mounted.

To demount the clips from the tapes it is necessary to place a portion of the tape in the wedge-shaped slide and then move the tape into the eye pulling the end of the tape 105 through the eye and out of the clip, as in Figure 15.

Turning to the principal feature of this invention, it will be observed that I have provided a supporting hook 27 which has a lat- 110

erally turned end 28 that can be detachably mounted in either of the two struck up arcuate cavities formed by the arcuate semi-circular tubular portion 29 of the back plate 30.

The rear wall 19 is directly beneath this back plate and prevents inward movement of the end 28 of the hook 27 beneath this rear wall 19, and directly beneath the back plate 30 is spreading arm plate 31 having prongs 32 which pass through the back plate into slots 33 in the back plate 30 and turn over upon the back plate, thus clamping several members to one another.

The spreading arm plate is provided with a pair of eyes 34 which receive the outwardly turned ends 35 of the U-shaped spreader arm 36. The outer end of this arm travels in a guide slide 37 of a guide plate 38 which is provided with side flanges 39 to strengthen it and an upwardly extending hinge member 40 which engages with the hinge member 41 on the spreading arm plate 31. This guide plate 38 has a tongue 42 which extends within the slot 43 in a supplementary re-inforcing paper member 44 which is pasted to the inside of the front and rear walls 19 and 20. This member 44 is interposed between the rear wall of the spreading arm plate and the prongs 32 of the spreading arm plate pass therethrough to further clamp it in position. The spreader arm 36 cannot be detached from the guide slide 37 because the guide slide 37 is closed at both ends which limits the movement of the spreader arm 36. The spreader arm is at the bottom of this guiding track or passageway when it is in spread position and slides to the top of this guiding track or passageway when it is in collapsed position. Thus, when the hook carrying the garments is mounted on the spreader arm it will be held in horizontal position and in spreading position with its sliding end at the bottom of the guiding passageway. Thus, the bag is spread positively and firmly to provide the necessary area for reception of the clothes in the bag. Any detachment of the spreading arm 36 from the guide slide 37 is prevented by the closed ends of the guide slide 37 and by the pivotal mounting of the spreading arm, as indicated.

It will be noted that, when the bag is spread open by the spreading arm 36 coat hangers 45 can be mounted thereon.

Referring to Figure 10, it will be observed that the bag is so folded that, when the hook 27 is folded downwardly it will have its hinge portion 28 and the rest of the supporting mechanism opposite to and adjacent the reinforced bottom of the bag composed of the sections 5 and 6 so that any weight on the bag will not cause any abrasion or tearing of the bag by reason of this metallic portion 65 engaging the thin walls of the bag, but, to

the contrary, the mechanism which might be damaged folds against the reinforced bottom of the bag where it cannot injure the more delicate sections of the bag.

It will be observed that I desire to comprehend within my invention such modifications as may be necessary to adapt it to varying conditions and uses.

Having thus fully described my invention, what I claim as new and desire to secure by Letters Patent, is:—

1. A new article of manufacture for use as a garment bag, consisting of a bag adapted to be folded in flat condition, means for maintaining the bag in spread condition 80 when it is unfolded and to support garments therein, the weight of said garments maintaining the spreading mechanism in spread position.

2. In combination in a garment bag, a bag body having a side opening, means to support the bag and means moving relative to the supporting means for spreading the bag to receive garments through the side opening, and means for connecting said spreading means and said bag support whereby the spreading means is adapted to support garments in the bag while the weight of the garments hold the bag in spread position. 90

3. In combination, a garment bag, a supporting means, a back plate connected thereto, a spreading arm plate inside said bag connected to the bag and to the back plate, a spreading arm mounted thereon pivotally, a guide plate mounted on said bag, means thereon to guide said spreading arm, said parts being so arranged that in their expanded position the bag will be held open and in their collapsed position the bag will be folded flat. 105

4. In combination, a garment bag, a supporting means, a back plate connected thereto, a spreading arm plate inside said bag connected to the bag and to the back plate, a spreading arm mounted thereon pivotally, a guide plate mounted on said bag, means thereon to guide said spreading arm, said spreading arm plate and said guide plate being hinged together. 110

5. In combination, a garment bag, a hook to support the bag, a back plate to pivotally connect said hook to the bag, a spreading arm plate, a spreading arm, a guide plate, means on the guide plate for guiding the spreading arm, means on the back plate for attaching it to the bag and means on the guide plate for attaching it to the bag. 115

6. In combination, a garment bag, a hook to support the bag, a back plate to pivotally connect said hook to the bag, a spreading arm plate, a spreading arm, a guide plate, means on the guide plate for guiding the spreading arm, means on the back plate for attaching it to the bag and means on the guide plate for attaching it to the bag, said 125

spreading arm plate and guide plate being hinged to one another.

7. In combination, a garment bag, a hook adapted to fold parallel to the bag pivotally mounted on a back plate, a back plate, a reinforcing member within the upper portion of said bag parallel to its walls, a spreading arm plate within said re-inforcing member, means on said spreading arm plate for joining said plate, re-inforcing member, bag wall and back plate together, a spreading arm pivoted on said spreading arm plate, a guide plate on the other wall of said bag within said re-inforcing member, means on said guide plate for being projected through said re-inforcing member between it and the bag wall and means to hinge said guide plate and spreading arm plate to one another.

20 8. In combination, a garment bag, a sup-

porting means, a spreading arm plate, a spreading arm, a guide plate having means through which said spreading arm is passed to retain it in permanent engagement with the plate but adapted to slide relative thereto, and means for attaching said guide plate and said spreading arm plate to said bag.

25 9. In combination, a garment bag, means to support the bag, a spreading arm plate, a U-shaped spreading arm pivoted thereon, 30 a guide plate, a guide trackway passing through said U-shaped end of the spreading arm so that the arm can slide on the guide plate but not become detached therefrom, and means of attaching said spreading arm 35 plate and said guide plate to said bag.

In testimony whereof, I affix my signature.

JOHN R. KLIN.
